AMALGAMATOR FOR SEPARATING NOBLE METALS

Heinrich Dverzsák, Kremnice, and Alexander Valentényi, Vyhne, Czechoslovakia, and Karl Kachelmann, Ujpest, Hungary

Application November 30, 1935, Serial No. 52,428
In Czechoslovakia December 3, 1934

3 Claims. (Cl. 209—62)

The invention relates to a type of apparatus called amalgamators, rendering possible the separation of such noble metals present in freely accessible condition in ores as will form amalgam with mercury, the ores being charged into the amalgamator in the form of slime suitably prepared for treatment.

An embodiment of the invention is illustrated by way of example on the drawing.

10 Figs. 1 and 2 are a longitudinal and a cross-section, respectively, of the amalgamator, Figs. 3 and 4 of the amalgam plates, Fig. 5 shows the arrangement of the shower-spray in the amalgam collector.

15 The machine consists of a closed casing, in which a system of amalgam plates 18, fixed in a position parallel to the shaft on two discs 14, 16 rotates around a horizontal shaft 13. These amalgam plates are silver-plated copper sheets 20 coated with mercury.

The casing consists of a cylinder 1, of a lateral wall 2 with charging hopper and a second lateral wall 3 with removable lid. The casing is fitted below with a drain opening 5 capable of being 25 closed, which is used for the discharge of the contents of the machine after the latter has been shut down. On the side opposite to that on which the drain opening is provided the casing is along its whole width constructed in the shape of a box, and serves here as an amalgam collector 6 which 30 likewise is capable of being completely closed. In this chamber a shower-spray 7 is installed through which clean water is introduced under pressure, in order to prevent, by its continuous 35 flow, any settling of the slime in this chamber. The extension of the amalgam collector is constructed along its whole width as a discharge gutter of the slime. The charging hopper provided on the lateral wall 2 is connected with the 40 upper chamber of the casing by a pipe elbow 8a, in order to enable the apparatus to be vented and in order to lead off any overflow. On this lateral wall a bracket for accommodating a bearing, a stuffing-box, an opening through which the 45 slime flows over into the plate system, a pipe branch 9 through which clean water is flowing under pressure, in order to seal the casing against the hopper, a second pipe branch 10, for enabling the stuffing-box to be sealed by means 50 of water under pressure, and the opening 11 for the admission of the mercury are provided. The lower part of the lateral wall is designed in the manner of a sole-plate and serves for fixing the machine to the foundation.

55 On the lower half of the second lateral wall 3

there are provided likewise a bracket for accommodating the second bearing, a stuffing-box, and a pipe branch 12 serving for the admission of the water under pressure into the stuffing-box. Below, the lateral wall is likewise shaped as a sole-plate. The upper, removable half of the lateral wall 4 (also called lid) serves for giving access to the plate system and for enabling the plates to be removed or inserted through this opening. The lid 4 and the blind flanges 5 and 6 are fixed to the flanges by means of bolts, but can also be made inaccessible, in such a manner that it is possible to keep them completely locked off in a suitable manner. The shaft 13 runs over the two stuffing-boxes and is supported in the bearing supported 10 on the brackets. Driving takes place by means of a pair of gear wheels through a pulley.

The main part of the amalgamator is the system of amalgam plates which is keyed on the shaft and is composed of the following parts: of 20 a disc 14, the hub of which is designed as an inlet opening, of a spider 15 with arms made of round bars, of a disc 16 consisting of two parts, of a number of concentrically arranged bars 17 of steel and of the amalgam plates 18. The bars 25 are fixed on one end to the disc and on the other end to the arms of the spider, the external bars being moreover also fixed on the disc consisting of two parts. The bars are slotted on both sides for receiving the plates. After the plates have 30 been inserted into the corresponding slots the plates are forming a number of octagonal tubes or prisms. The internal amalgam plates are shorter than the bars and are alternately leaning against the lateral discs, so that openings are 35 formed between the discs and the plates, through which openings the slime flows from one prism into the other. The external plates are of the same length as the bars and are fitted with separate discharge openings, through which the slime 40 leaves the amalgamator. The plates are fixed in their positions by a bolt 19 and rubber cushions 20. The disc 16 consisting of two parts is fixed in the middle to the spider 15 and on its external periphery to the bars. Stirring vanes 21 are 45 provided on the external side of the discs and stirring angles 22 on the external bars. The stirring vanes and angles serve for stirring the slime in order to prevent any settling.

The machine operates in the following manner: 50 The slime flows through the hopper into the apparatus and fills the whole of the casing, and leaves the machine in due course through the discharge gutter. The amalgam plates are during all the time immersed into the slime in their 55

entire extent, without coming into contact with the atmospheric air. The larger grains of noble metal will fall to the ground in the first tube already and become amalgamated. The more fine the condition into which the ores are brought, the later will the grains of noble metal come into contact with the plates, and for this reason it is necessary to pass the slime through tubes or prisms the diameters of which are constantly increasing in order to diminish the flow velocity of the slime, so as to give occasion even to the smallest particles to come into contact likewise with the plates. The fact that the prisms are of octagonal shape and are rotating increases the possibility of contact. The slime leaving the amalgam plates, which now already contains only the sizes of grain not sufficiently opened up or those bound, passes through the discharge opening into the flotation plant, lye plant etc. for the purpose of being subjected to further treatment. As it is only a certain quantity of ore (not exceeding 20%) that the mercury is able to amalgamate, it is necessary to effect a supplementary feeding of mercury through the opening 11.

Any particles of amalgam or mercury which may possibly become detached from the plates will drop into the casing and will be passed by the flow of the slime and by the trailing action of the stirring devices into the amalgam collector. In order to remove the amalgam adhering to the plates the lid 4 and the disc 16 are removed, whereby the plates will become ready for being removed from the apparatus.

The amalgamator according to the invention possesses the great advantage, as compared to the known types of amalgamators, that owing to the gradually diminishing flow speed, the particles of noble metal contained in the slime have occasion, during a relatively considerable length of time, for coming into contact with a large amalgam surface, i. e. for becoming amalgamated. This method of operation ensures the further ad-

vantage that the fine and flat particles of noble metal will also be retained by adhesion on the plates, whereby the yield percentage will be substantially increased.

Another advantage of the apparatus consists in the fact that the amalgam collector is built into the machine itself whereby the loss in metal and mercury is substantially diminished.

Finally we would mention the advantage, the importance of which should not be underrated, that the closed arrangement renders access to the valuable amalgam impossible for unauthorized persons, i. e. prevents any stealing of gold.

What we claim is:

1. An amalgamator for treating materials containing precious metals, comprising a closed rotatably mounted drum, and a plurality of plates alternately secured to the opposite ends of the drum with the free ends of the plates overlapping each other and forming therewith a zigzag path of flow of the material, said plates forming annular members concentric with the drum whereby the flow of the material extends axially of the axis of the drum.

2. An amalgamator according to claim 1 in which a lid is provided in the drum and the plates are removably secured so that said plates may be removed from the drum through an opening covered by the lid.

3. An amalgamator for treating materials containing precious metals, comprising a closed rotatably mounted drum, and a plurality of plates alternately secured to the opposite ends of the drum with the free ends of the plates overlapping each other and forming therewith a zigzag path of flow of the material, said plates forming annular polygonal members within the drum whereby the flow of the material extends axially of the axis of the drum.
